OIL BURNER

David A. Jones, Webster Groves, Mo.

Application September 3, 1940, Serial No. 355,228

3 Claims. (Cl. 122—10)

This invention relates to oil burners and more particularly to an improved oil burner structure and an improved means for vaporizing or atomizing the oil in a furnace.

An object of this invention is to provide a burner or nozzle, which is adapted to be connected to an oil supply line and which is also adapted to be connected to a steam forming coil, so that the steam formed in the coil will provide the necessary suction means for withdrawing the oil from the oil supply source.

Another object of this invention is to provide an improved oil burner structure, which may be easily and quickly mounted in a conventional furnace structure and which eliminates the use of any moving parts in the furnace so that the burner will not readily get out of order.

A further object of this invention is to provide an oil burner structure including an oil vaporizing nozzle and means for generating steam, so that the steam may not only form a means for preheating and atomizing or vaporizing the oil, but also form a means for withdrawing the oil from the supply source.

A still further object of this invention is to provide a burner of this type including a means for initially generating steam in the steam generator, the means for initially generating steam being in the form of a pilot burner, which may be connected to a source of gas or other combustible fuel supply.

To the foregoing objects and to others which may hereinafter appear, the invention consists of the novel construction, combination and arrangement of parts, as will be more specifically referred to and illustrated in the accompanying drawing, wherein is disclosed an embodiment of the invention, but it is to be understood that changes, variations and modifications may be resorted to which fall within the scope of the invention as claimed.

In the drawing:

Figure 1 is a detail side elevation of a burner structure constructed according to an embodiment of this invention mounted in a conventional furnace structure, and

Figure 2 is an enlarged fragmentary longitudinal section taken through the nozzle and the lower portion of the steam generator or boiler.

Referring to the drawing, the numeral 10 designates generally a furnace of conventional construction, it being understood that the hereinabove described invention may be mounted in any suitable furnace, which may include a feed door structure 11, clinker door structure 12 and ash

door structure 13. The furnace 10 may either be a hot air or hot water furnace, or if desired may be a small steam boiler.

A steam generator or coil, generally designated 5 as 14, is adapted to be positioned within the interior of the furnace 10 and the generator 14 in the present instance is constructed from a single length of pipe, which is bent in substantially V-shape with one side 15 thereof adapted to be in an uppermost position and inclined to the horizontal and the other side 16 thereof, which is connected to the upper side 15 by an arcuate connecting member 17, is inclined to the horizontal and inclined reversely from the inclination of the upper side 15. The upper side 15 is adapted to be connected by means of a coupling 18 to a water supply pipe line 19. A cutoff valve 20 is interposed in the water supply line 19 and at a point between the cutoff valve 20 and the coupling 18 a water limiting valve 21 is interposed in the pipe line 19. A pressure gauge 22 may be connected to the pipe line 19 between the coupling 18 and the limiting valve 21.

At a point between the two valves 20 and 21, 25 I have preferably provided an electrically operated valve member 23, which may be connected to a suitable source of electric supply and this valve 23 may be of a type which will automatically cutoff the water supply in the pipe 19 under temperature conditions or the like. The valve structure 23 is a conventional electrically operated cutoff valve, the details of which are well known. A pressure reducing valve 24 is interposed in the pipe 19 between the valve 21 and the electrically operated valve 23, so as to reduce the pressure from the water supply before the water passes the limiting valve 21. By means of the pressure reducing valve 24, which is of conventional construction, the water passing the limiting valve 21 will gravitatingly flow through the remainder of the pipe 19 and then downwardly through the steam generator member 15 through the arcuate connecting member 17 and into the lower steam generating member 16. Preferably 35 in order to retard the flow of water in the generator 14 and to also assist in more rapidly generating steam within the generator 14, I have mounted in the generator 14 a plurality of wire strands 25. These wire strands are preferably 40 formed of metal which is highly heat conducting so as to assist in the rapid generation of steam within the generator 14.

A combined oil burner and atomizing nozzle, generally designated as 26, is adapted to be positioned within the furnace 10 at a point slightly

above the lower generator member 16 and in a position substantially parallel with the generator member 16. The nozzle member 26 comprises an outer nozzle member 27 in the form of a cylindrical body, which at its forward end is formed with a jet or frusto-conical member 28. The rear end of the cylindrical member 27 has mounted thereon a cap 29 threaded onto the outer nozzle member 27. An inner steam nozzle member 30 is disposed coaxially within the outer nozzle member 27 and is formed, at its forward end, with a jet member 31, which is positioned slightly inwardly from the forward end of the jet member 28. The steam nozzle member 30 extends axially through the rear wall 32 of the cap 29 and is connected to an L coupling member 33.

A short pipe member 34 is connected to the L 33 and the pipe 34 is connected to one side of a second L 35. The L 35 has a nipple 36 mounted in the other side thereof and the nipple 36 engages in a rear wall 37 of a cap 38. The cap 38 is threaded onto the lower or rear end of the lower generator member 16. The steam nozzle member 30 may be secured in the end wall 32 in any suitable manner, such as by welding 39 or the like.

The outer nozzle member 27 has secured thereto, at a point intermediate the ends thereof and preferably at a point closely adjacent the rear end, a laterally extending intake nipple 40. The nipple 40 is connected to one side of an L 41 and a fuel supply pipe 42 is connected to the other side of the L 41. The supply pipe 42 may have a cutoff valve 43 interposed therein and is adapted to be connected to a reservoir 44. The reservoir 44 is in the form of a small tank, which is adapted to be connected by means of a pipe 45 to a main supply tank. The oil is preferably discharged into the tank 44 by gravity.

In order to provide a means whereby steam may be initially generated in the steam generator 14, I have provided a gas burner member 46 positioned below the lower generator member 16, which is secured to the lower member 16 by means of a bracket member 47. The burner 46 may be disposed in substantially parallel relation with the lower member 16 on the generator and is adapted to be connected to a supply pipe 48, which has a cutoff valve 49 interposed therein.

In the use and operation of this burner structure the pilot burner 46 is initially lighted by opening the valve 49 so as to permit gas or other fuel to pass to the burner 46. The valve 20 may be initially opened and the valve 21 also initially opened to the desired degree, so as to permit the water to gravitatingly flow through the pipe 19 and then down through the upper generator member 15 through the arcuate connecting member 17 and into the lower generator member 16. The electrically operated valve 23 may be controlled by a thermostat, or other suitable electrical means, which will cut off the flow of water when the desired temperature at a particular point has been attained. The wire strands 25 in the generator 14 will assist in the generation of steam and after steam has been generated, this steam will pass through the nipple 36, the coupling member 35, the short pipe 34, the coupling member 33 and pass through the steam nozzle or jet member 30. The steam will be discharged from the jet 31 of the nozzle member 30 and as the steam is discharged through the open end 50 of the jet 28, it will act to draw oil through the pipe 42 and nipple 40 into the nozzle member 27. The discharging steam will not only

act in a manner as aforesaid, but will also act as a means for preheating the oil and in addition for breaking up the oil into a spray. In this manner the oil will readily ignite and once the oil has been ignited, the flame from the burner member 26 will be discharged in the direction of the arcuate connecting member 17 of the generator 14.

This will have the effect of generating steam in the arcuate connecting part 17. After the burner 26 has been ignited and sufficient steam generated to draw in sufficient oil from the tank 44 to operate the burner 26, the pilot burner 46 may be cut off. The back pressure from the generator 14, which extends through the pipe 19 to the valve member 21 and the pressure reducing valve 24, will have the effect of automatically controlling the amount of water which will pass to the generator 14. This amount of water may also be controlled by regulation of the pressure reducing member 24 and the limiting valve 21.

A burner structure constructed according to this invention may be positioned in any conventional furnace structure, and as there are no moving parts in the generator or burner proper, the device will not readily get out of order. This burner may be constructed at a relatively small cost in view of the simplicity of its construction and the simplicity of its operation.

The position and form of the generator 14 allows the water to freely flow by gravity from the upper end to the lower end of the generator, except for the loose strands of wire 25. The strands 25 coact with the generator 14 in effecting a quick exchange of heat so that there will not be formed any trapped water or trapped steam. This novel construction makes the burner structure particularly adaptable to automatic operation. The automatic control of the water passing to the generator controls the section of oil so that more or less flow of water will have a corresponding effect on the flow of oil.

The burner structure may be cut off by either cutting off the flow of water which will cut off the suction of oil, or the oil valve may be closed.

What I claim is:

1. A steam generator for connection to an oil atomizing nozzle comprising a V-shaped steam generator having its legs disposed in superposed relation and its base upstanding and merging into the inner ends of said legs, a closure cap on the outer end of the lower one of said legs, and a tubular steam conductor connected to said cap and to said nozzle, said conductor supporting said nozzle closely adjacent to and in parallel relation with respect to said lower leg whereby the flame emanating from said nozzle will encompass the inner portion of said lower leg and impinge against the lower portion of said base.

2. A steam generator for connection to an oil atomizing nozzle comprising a V-shaped steam generator having its legs disposed in superposed relation and its base upstanding and of longitudinally arcuate configuration, and merging into the inner ends of said legs, a closure cap on the outer end of the lower one of said legs, and a tubular steam conductor connected to said cap and to said nozzle, said conductor supporting said nozzle closely adjacent to said lower leg whereby the flame emanating from said nozzle will encompass the inner portion of said lower leg and impinge against the lower portion of said base.

3. A steam generator for connection to an oil

atomizing nozzle comprising a V-shaped steam generator having its legs disposed in superposed relation and its base upstanding and merging into the inner ends of said legs, a closure cap on the outer end of the lower one of said legs, a tubular steam conductor connected to said cap and to said nozzle, said conductor supporting said nozzle closely adjacent to said lower leg whereby

the flame emanating from said nozzle will encompass the inner portion of said lower leg and impinge against the lower portion of said base, and a plurality of metallic strands possessing a high heat conducting characteristic arranged in said lower leg.

DAVID A. JONES.
